UNITED STATES PATENT OFFICE.

JOHN M. PALMER, OF NASHVILLE, TENNESSEE.

IMPROVEMENT IN CLOTH-MEASURING MACHINES.

Specification forming part of Letters Patent No. **154,895**, dated September 8, 1874; application filed June 8, 1874.

To all whom it may concern:

Be it known that I, JOHN M. PALMER, of Nashville, in the county of Davidson and State of Tennessee, have invented certain Improvements in Cloth-Measuring Machines, of which the following is a specification:

My invention consists in a pair of cylinders, the upper one of which has on its shaft a pinion driving a toothed wheel provided with pointers and dial-plates for indicating the number of revolutions, and with a projection for striking a lever to sound a bell, the lever being formed with a knife-handle joint, to allow the motion of the rollers to be reversed without sounding the bell.

In the accompanying drawing, Figure 1 is a longitudinal vertical section of my improved cloth-measuring machine. Fig. 2 is a transverse vertical section taken in the line $x-x$ of Fig. 1. Fig. 3 is a transverse vertical section taken in the line $y-y$ of Fig. 1. Fig. 4 is a face or end view.

The upper cylinder, B^1 , is journaled in stationary bearings in the main frame A of the machine. On the front end of its shaft is a pinion, b' , which drives a gear-wheel, C , on both ends of the shaft of which are pointers c^1 c^2 , for indicating on dial-plates D^1 D^2 the number of revolutions of the cylinder B^1 . The dial D^1 is arranged on the outer end or face of the machine, and the dial D^2 on the inner portion of the frame above the cylinder B^1 . On the outer side of the gear-wheel C is a stud or projection, e , which, as the wheel revolves, depresses one end of a lever, F , on the other end of which is a hammer, g , which strikes a gong, G . The lever F is pivoted to the frame A , and provided with a spring, h , for holding it in the position shown in Fig. 3. Between the fulcrum and the point of engagement of the stud e the lever is formed with a knife-handle joint, f , which allows it to bend upward but not downward, so that, when the wheel C revolves in the direction of the arrow, the stud e depresses the lever and strikes the bell; but when the motion is reversed, the stud raises the jointed portion of the lever, and passes readily by it without sounding the bell.

The lower cylinder, B^2 , is journaled in blocks J J , under which are springs i i , resting upon sliding bars K K . These springs serve to keep the cylinder B^2 pressed against the upper cylinder, and allow it to yield and adjust itself to cloth of different thicknesses. The bars K K are provided with racks l l , which engage with pinions m m on a shaft, n , furnished with a lever, p , by which means the pressure of the lower cylinder upon the upper is regulated at pleasure.

In the frame A , at one side of the indicating mechanism, is journaled a shaft, Q , carrying a toothed wheel, q , driven by a pinion, r , on a shaft, R , which receives its motion from the wheel C . The shaft Q carries a pointer at each end, said pointers revolving outside of dial-plates S^1 S^2 , arranged beside the dial-plates D^1 D^2 . The pinion r is loose on the shaft R , and is caused to revolve therewith by means of a clutch, t , provided with a rod, s^2 , for throwing it out of engagement, and a spring, s , for holding it engaged with the pinion r . The shaft Q is provided with a spring, U , which draws it back when the clutch is disengaged.

As the cylinders B^1 B^2 revolve, when the wheel C and its pointers make a complete revolution the shaft Q is revolved sufficiently to cause the pointers on its ends to indicate the same on the dial-plates S^1 S^2 , and thus register the number of revolutions of the cylinders. By withdrawing the rod s^2 , and disengaging the clutch, the shaft Q is reversed by the spring v .

What I claim as new, and desire to secure by Letters Patent, is—

The combination, with the cylinders B^1 B^2 , of the gear-wheel C , having a stud, e , the lever F , having the knife-handle joint f and hammer g , and the gong G , the whole being constructed to operate as and for the purpose described.

JOHN M. PALMER.
